STRING FOR MUSICAL INSTRUMENTS

Stanley Kaplan, Norwalk, Conn., assignor to
Kaplan Musical String Co., Norwalk, Conn.

Application April 15, 1939, Serial No. 268,039

8 Claims. (Cl. 84—297)

This invention relates to improvements in strings for musical instruments.

It is an object of the present invention to provide a musical instrument string which not only is capable of producing a tone of high quality, but is substantially unaffected by moisture or change in temperature.

Because of their light weight and proper elasticity, gut strings, from the standpoint of tone, have been considered superior to all others. For example, the violin A strings now in general use are for the most part gut strings. In spite of the fine tonal quality of gut strings, however, they are open to the very definite disadvantage of being highly susceptible to moisture as from perspiring fingers or from the air and under the influence of which the gut softens up, becoming rough and uneven and frequently causing the strands to separate.

Moistureproofing in the processing of gut has been used with some success, but, it has been found, results in a harder, more brittle gut which gives the string a harsh tone. No known treatment of the surface of gut strings is of avail, because, due in part to the necessary stretching of the string on the musical instrument, the finish does not stick to the gut permanently.

Various alternatives to plain gut strings have been proposed. One such proposal that has been used involves a string having a core of steel, wound with aluminum wire and having an underlay of silk floss, braided silk or the like. However, aluminum wound steel strings have a very harsh metallic tone which even a braided silk underlay does not entirely eliminate.

Another alternative string involves a gut core with aluminum wire wound thereon. Such a string has been found to have a good tone, but with such strings it is necessary to use a very thin foundation or core which frequently does not have adequate strength. Moreover, the aluminum wire too, must be extremely thin, .00375 inch in the case of violin A strings, with the result that any expansion of the gut core breaks up the winding. Also, it has been found that such strings wear through after a relatively short period of use. If the size of the gut core is increased to gain strength, the weight and tension of the string on the instrument is increased, making the tone harsh and unresponsive. Increasing the thickness of the aluminum wire also increases the weight and places a greater strain on the string, increasing the possibilities of premature breakage. Moreover, aluminum wound strings, particularly A strings, must be made within such close limits that only the most care-

ful selection of materials makes them at all feasible.

Also, because of the very high heat conductivity of aluminum and its high coefficient of expansion, strings wound with this material are greatly affected by temperature changes, as brought about by changes in the temperature of the air or by the heat of the fingers in playing, so that they lack stability of pitch.

Moreover, although aluminum strings are carefully polished after winding to make them as smooth as possible, the expansion of the gut under the thin wire causes a roughness for which they are frequently rejected, a problem difficult to overcome because of the lack of strength of such thin soft wire. A further disadvantage of strings wound with aluminum wire is that the wire blackens the fingers of the players.

It is, therefore, another object of the invention to provide a string which overcomes the above enumerated disadvantages of aluminum strings.

To these ends, there is provided as a feature of the invention a musical instrument string involving the utilization of a synthetic plastic fiber such as nylon, such string having a gauge or characteristics substantially the same as a standard gauge of a string of known designation.

Another feature of the invention resides in providing a string having a core of metal, gut or nylon, about which is wound nylon fiber.

Advantages flowing from the utilization of nylon fiber in a musical instrument string include the provision of a string that has a tone as mellow and responsive as the best gut string; that is substantially impervious to moisture, or to perspiration or like body acids; that is substantially unaffected by changes in temperature, thus maintaining accurate pitch so essential in public performance; that has a superior smoothness of surface; that has wearing quality superior to that of aluminum wound string; that will not be roughened under the action of the fingers in playing; and that will have great durability.

Other objects, features and advantages will hereinafter appear.

In the drawing:

Figure 1 is an enlarged fragmentary side view of a musical instrument string illustrating one form of the invention.

Fig. 2 is an enlarged fragmentary side view, partially in section, of the musical instrument string shown in Fig. 1.

Fig. 3 is an end view of the string shown in Fig. 2.

Fig. 4 is a view similar to Fig. 2 but showing a modified form of the invention.

Fig. 5 is a view similar to Fig. 2 but illustrating a further modified form of the invention.

5 Fig. 6 is an end view of the musical instrument string shown in Fig. 5.

Fig. 7 is an enlarged fragmentary side view of a musical instrument string illustrating another form of the invention.

10 Fig. 8 is an end view of the string shown in Fig. 7.

Before describing the present improvements and mode of operation thereof in detail it should be understood that the invention is not limited 15 to the details of construction and arrangement of parts shown in the accompanying drawing, which are merely illustrative of the present preferred embodiments, since the invention is capable of other embodiments, and the phraseology employed is for the purpose of description and not of limitation.

Referring more particularly to the drawing and first to Figs. 1, 2 and 3, there is shown a musical instrument string 12 looped and tied at one end 25 in the conventional manner to provide an eye 11 for attachment to a complementary element on the musical instrument with which it is to be associated.

Of particular importance, however, the string is 30 neither a plain gut string nor is it a string built up by winding aluminum wire about a core in the conventional manner. On the contrary it comprises a core 13 of gut with a synthetic plastic fiber strand 14 closely wound thereon to provide 35 an outer casing or covering and which, if desired, may be secured to the core by an adhesive 15. Of importance the fiber 14 is made of a material which, it has been found, has a specific gravity approximating animal gut, is insensitive and sub- 40 stantially impervious to moisture, has a high tensile strength, has an elasticity approximating gut, has a smoothness even after polishing and wearing away, has a high resistance to wear, is a substantial nonconductor of heat so that it is not 45 affected by temperature changes, and has a flexibility which enables it to be most successfully wound about even a very small core.

This material of which the fiber 14 is made, and which in fiber form has been found to be 50 so well adapted for winding on a core in a musical instrument string, is a synthetic plastic material developed by E. I. du Pont de Nemours & Co. and called nylon, a generic name including all materials defined scientifically as synthetic fibers 55 forming polymeric amides having a proteinlike chemical structure.

Tests with plain unwound nylon fibers have given no indication that nylon would be a satisfactory material for musical instrument strings. 60 On the contrary such tests have shown that the quality and volume of tone produced by plain nylon fiber when strung in a musical instrument is so inferior and unsatisfactory that it could not be used as a substitute for plain gut string. The 65 eminently satisfactory results achieved, therefore, when nylon fiber, or nylon monofilament, was wound on a gut core were totally unexpected and contrary to the results anticipated in view of the inferior tonal qualities found by tests made 70 on unwound nylon fiber.

In comparing an aluminum wound string with a nylon wound string of the same type it is found that the gut core or foundation of the latter can be ten per cent larger in diameter, thus gaining 75 at least twenty per cent in tensile strength and

even with the thicker nylon covering, giving added strength and wear, the resultant tone is superior to the aluminum wound string.

Moreover, nylon fiber used in winding musical instrument strings not only has a far greater 5 strength than the aluminum wire, but it has a marked degree of elasticity which makes it possible to wind it tighter on the gut foundation or core 13, and even through an underlay of silk or the like such as the winding 16 shown in Fig. 5 10 may be used, such an underlay is not necessary with a gut core, as the nylon adjusts itself to any expansion of the core or foundation. And, as 15 nylon is unaffected by moisture, is moistureproof and a nonconductor of heat, the pitch of a string wound with nylon fiber or having at least an outer covering of nylon, is not affected by either atmospheric or temperature changes. A stability of 20 pitch is thus obtained which is not approached by any other known type of string. Such a nylon 25 wound string is adaptable to any musical instrument requiring the thickness or specific gravity of gut strings, and while producing a tone as mellow and responsive as the best gut string, is, because of its superior durability and strength, its 30 quality of being substantially unaffected by moisture and its superior surface smoothness, much more satisfactory than gut string.

If desired, and as shown in Fig. 4, the nylon 35 winding utilized may be built of a plurality of 40 separate strands 17 of fiber and this, whether a gut core 13 such as shown in Fig. 2 is used, or a 45 nylon core 18 such as in the modified string 19 shown in Fig. 4 is used. As with the string 12 shown in Fig. 2, an adhesive 15 may, as shown, be 50 interposed between the nylon winding and the 55 core, and it will also be appreciated that a winding of a single strand 14 of fiber such as shown in Fig. 2, may be utilized on the nylon core 18 shown in Fig. 4.

For extreme dependability and strength, a modified string 20, such as shown in Figs. 5 and 6, 55 may be utilized, characterized by a strong core 21 of metal, such as steel. A winding of a single 60 strand 22 of nylon fiber, as in the string 12 shown in Fig. 2, may be used on the steel core, but it 65 will be readily understood that, if desired a nylon winding made up of a plurality of separate 70 strands, such for example as shown in Fig. 4, 75 may be used.

Preferably, and in order to overcome any tendency of the string 20 with the metal core 21 to 80 produce a tone which is too metallic, a layer of 85 silk or the like such as provided by the silk winding 16 is interposed between the nylon winding 90 and the core and, as shown, may be secured to the core by an adhesive 15. As hereinbefore 95 explained such an intermediate layer may also be used in the string 12 having a gut core 13, and if desired may also be utilized in the string 19 having a nylon core 18.

While, as shown in Figs. 1, 2, 3, 4, 5 and 6, 100 the nylon fiber used in winding the string is substantially round, this shape is not essential 105 since after the strings are wound they are polished or sandpapered to provide a smooth outer 110 surface. Thus, as in the string 23 shown in Figs. 115 7 and 8, a substantially flat nylon fiber 24 may be wound about a core 25 which, for example, 120 may be of gut as in Fig. 2, of nylon as in Fig. 4, 125 or of metal as in Fig. 5. Also, it is to be understood 130 that the size of the core and the thickness 135 of the nylon fiber may be varied to determine 140 the ultimate pitch of the string.

Variations and modifications may be made 145

within the scope of this invention and portions of the improvements may be used without others.

Having thus described the invention, what is claimed as new is:

5. 1. A string for a musical instrument, having a diameter substantially the same as that of a gut string of known designation, comprising a core of tensile strength substantially the same as that of gut; and a wrapping of synthetic polymeric 5 amide filament wound on said core.

10. 2. A string for a musical instrument, having a diameter substantially the same as that of a gut string of known designation, comprising a gut core; and a wrapping of synthetic polymeric 10 amide filament wound on said core.

15. 3. A string for a musical instrument, having a gauge that is substantially the same as a standard gauge of a string of known designation, comprising a core; and a wrapping of synthetic polymeric 15 amide filament wound on said core.

20. 4. A string for a musical instrument, having a specific gravity substantially the same as that of a gut string of known designation, comprising a gut core; and a winding of nylon filament on 20 said core.

25. 5. A string for a musical instrument, having a

specific gravity substantially the same as that of a gut string of known designation, comprising of a gut core; and a filament winding on said core of a material having a specific gravity and an elasticity approximating that of gut, having high 5 tensile strength and being substantially imper-
vious and insensitive to moisture.

6. A string for a musical instrument, having a specific gravity substantially the same as that of a gut string of known designation, comprising 10 a core; and an outer covering of nylon filament wound on said core, said core being of metal wrapped with silk or the like.

7. A string for a musical instrument, having a thickness substantially the same as that of a 15 gut string of known designation, comprising a gut core; and a wrapping of substantially flat synthetic polymeric amide filament wound on said core.

8. A string for a musical instrument, having a thickness substantially the same as that of a gut string of known designation, comprising a gut core; and a plurality of separate strands of 20 nylon filament wound on said core.
